CIGARETTE BOX

Curtis Block, Bridgeport, Conn.

Application October 25, 1947, Serial No. 782,201

9 Claims. (Cl. 312—77)

1

This invention relates to new and useful improvements in dispensing devices and has particular relation to a cigarette box adapted to receive a number of cigarettes and on proper manipulation to dispense or expose the cigarettes one at a time.

An object of the invention is to provide a cigarette box including a base, a cigarette receptacle slideable on the base from end to end thereof, a rocker element in the base and at its respective ends provided with supports each adapted to receive a cigarette, and means whereby when the receptacle is at one end of the base a cigarette is deposited on a support and as the receptacle is moved to the other end of the base the element is rocked to raise said support and expose the cigarette for ready removal from the box.

Another object is to provide a cigarette box including an elongated base having a slot-like opening adjacent each end, a pair of supports movable inwardly and outwardly through the respective openings, a receptacle slideable on the base from end to end thereof, and means whereby as the receptacle is moved to one end of the base the receptacle deposits a cigarette in the support at said end of the base and causes the support at the other end of the base to move outwardly through the slot at said end of the base.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention and the scope of the appended claims.

In the drawing:

Fig. 1 is an isometric view of the cigarette box of the invention prior to covering of the same by leather or other ornamental means;

Fig. 2 is a vertical central longitudinal sectional view through the box of Fig. 1, the receptacle thereof being in an intermediate position;

Fig. 3 is a view similar to Fig. 2 but showing the receptacle in an end or dispensing position; and

Fig. 4 is a vertical transverse sectional view taken as along the line 4—4 of Fig. 3.

Referring in detail to the drawing, the improved cigarette box is shown as including broadly a hollow elongated base generally designated 10 and a receptacle mounted on and movable along the base and generally designated 11. The

2

base 10 includes a bottom wall 12, side walls 13 and 14, ends 15 and 16 and a top wall 17 stopping short of each of the ends whereby slots or openings 18 and 19 are formed immediately inwardly of the respective ends and extending transversely of the base between the side walls 13 and 14 thereof.

Within the base is a rocker element 20 having a pivot point 21 midway its ends and at the respective sides of said pivot point comprising arms 22 and 23 extending substantially to the inner sides of the ends 15 and 16 of the base. Trough-like supports 24 and 25 are supported from the outer or remote ends of the respective arms 22 and 23 in alignment with the slots 18 and 19 respectively and are adapted to move inwardly and outwardly through said slots as the rocker element 20 is rocked, all as will later be described in detail.

Stop blocks 26 and 27 may be provided under the outer ends of the respective arms 22 and 23 of the rocker element to limit rocking movement of the latter. In the top wall 17 of the base, toward the respective ends thereof, openings 28 and 29 are provided and mounted on the upper ends of the rocker element arms 22 and 23 are knobs or knob-like portions 30 and 31 movable inwardly and outwardly through the openings 28 and 29, respectively.

Longitudinally extending ways or guideways 32 and 33 are provided in the inner sides of the side walls 13 and 14 adjacent the upper edges of the latter and the receptacle 11 is mounted on the top wall 17 of the base and provided with a pair of laterally extending flanges 34 and 35 at its lower side edges. These flanges are disposed in the ways 32 and 33 whereby the cigarette receptacle 11 is mounted for sliding movement longitudinally of the base 10.

In addition to the flanges 34 and 35, receptacle 11 includes side walls 36 and 37, end walls 38 and 39, a top wall 40 and a bottom wall or member 41. Wall 41 is secured to the side walls 36 and 37 and is centrally thickened so that from a point approximately midway between the end walls 38 and 39, its upper surfaces 42 and 43 incline outwardly and downwardly. However, this bottom wall 42 stops short of the end walls 38 and 39 whereby discharge openings 44 and 45 are provided between the extreme edges of the bottom wall 41 and the respective end walls 38 and 39. A vertical element 46 which is or may be integral with the bottom 40 provides for the further dividing of the interior of the receptacle 11 into a pair of compartments.

Through the upper or top wall 40, there is an opening 47 extending substantially completely across the receptacle and between the side walls 36 and 37 thereof. When the present cigarette box is used, this opening 47 is closed as by an ash receptacle 48 fitting into the opening, but such receptacle is, of course, easily slipped out of place for emptying and further is easily slipped out of place to permit of replacing a supply of cigarettes in the receptacle. In the present instance, the location of cigarettes within the receptacle is suggested by the broken lines at 49. If desired, a humidifying means (not shown) may be secured to the underside of the ash tray 48.

It is noted that the end walls 15 and 16 of the base are in the form of segments providing curved end surfaces and that the end walls 38 and 39 blend with the top wall 40 in the matter of the receptacle 11. While a covering is not shown in the drawing, since it would form no part of a mechanical patent, it is planned that the present device be covered with leather or other material whereby to provide a cigarette box of neat and attractive appearance. Such box could be used on a desk, library table or the like and be of attractive appearance as well as useful for its intended purpose.

As to the use of the present cigarette box, the filling of the receptacle 11 through the opening 47 when the ash tray 48 is removed has been described. Normally, the receptacle 11 would be positioned approximately midway the ends of the base as suggested in Figs. 1 and 2. In Fig. 2, it is noted that a cigarette is suggested by the broken lines 50 as disposed within the support 25. A person wishing to obtain a cigarette may, of course, simply lift it out of the support in Fig. 2 but generally the idea is that the receptacle 11 will be shifted toward the left in Fig. 2 as to the position of Fig. 3. There it will be noted that the bottom 41 of the receptacle has engaged the means or knob 30 and depressed the same, tilting the rocker element 20 so as to move the support 25 up through the slot 19 and position the cigarette 50 for convenient removal.

In the meantime, a cigarette from the receptacle has dropped through the discharge opening 44 onto the support 24 but such cigarette is yet covered by the receptacle. The receptacle may be left in this position. Then the next time a cigarette is desired, the receptacle is moved to an extreme right hand position and during such movement engages knob 31 rocking the element 20 so as to move the support 24 out through the slot 18 to dispose a second cigarette for convenient removal.

As the movement of the receptacle is continued toward the right, when it reaches its extreme position a cigarette is dropped through the discharge opening 45 onto the support 25. From this, it will be seen that simply by alternately shifting the receptacle 11 first to one end and then to the other end of the base, cigarettes are deposited through the discharge openings 44 and 45 of the receptacle, first in the support 24 and then in the support 25 and such supports are alternately shifted by the rocker element to projected and withdrawn positions.

Having thus set forth the nature of my invention, what I claim is:

1. In a cigarette box, an elongated hollow base including side and end walls and a top wall, said top wall stopping short of each of said end walls whereby slots are formed extending across the

base at each end of said top wall, a cigarette receptacle on said top wall, means mounting said receptacle for sliding movement longitudinally of said wall, said receptacle having a discharge opening toward each end of the receptacle, said receptacle slidable on said base from end to end thereof to dispose first one discharge opening over the slot at one end of the top wall and then its other discharge opening over the slot at the other end of said top wall, a rocker element in said base, a support on each end portion of said element and said supports located to move inwardly and outwardly through said slots as said element is rocked, said supports adapted to receive cigarettes discharged through the respective ends of the base, and spaced means on said rocker element and adapted to be engaged and depressed by the receptacle to shift first one and then the other of said supports through its slot as said receptacle is slid first to one and then to the other end of said base.

2. In a cigarette box, a cigarette receptacle slidable on said base from end to end thereof, a rocker element in said base, supports on the respective ends of said element and each adapted to receive and support a cigarette, said base having a slot-like opening through its upper side in alignment with said supports, and means whereby when said receptacle is at one end of said base a cigarette from the receptacle is on the support aligned with the slot-like opening at said end of the base and as the receptacle is moved to the other end of the base the rocker element is rocked to raise the support having the deposited cigarette and expose the latter for ready removal from the box.

3. In a cigarette box, an elongated base having a slot-like opening adjacent each end, a pair of supports movable inwardly and outwardly through the respective slots, a receptacle slidable on the base from end to end thereof, and means whereby as the receptacle is moved to either end of the base the receptacle deposits a cigarette in the support at said end of the base and causes the support at the other end of the base to move outwardly through the slot at said other end of the base.

4. In a cigarette box, an elongated base having a slot-like opening adjacent each end, a pair of supports associated one with each of said slots, a rocker element in said base, means whereby as said element is rocked said supports are moved in alternate order outwardly and inwardly through the respective slots, a receptacle slidable on the base from end to end thereof and adapted when moved to either end of the base to deposit a cigarette on the support adjacent that end, and means whereby sliding movement of said receptacle results in rocking of said element.

5. In a cigarette box, an elongated base having a slot-like opening adjacent each end, a pair of supports associated one with each of said slots, a rocker element in said base, means whereby as said element is rocked said supports are moved in alternate order outwardly and inwardly through the respective slots, a receptacle slidable on the base from end to end thereof and adapted when moved to either end of the base to deposit a cigarette on the support adjacent that end, a knob on said element toward each of its ends, said knobs adapted to be alternately engaged and depressed by said receptacle as it is moved back and forth between the ends of the base to rock said element and cause movements of said supports alternately outwardly through said slots.

6. In a cigarette box, an elongated hollow base including side and end walls and a top wall, said top wall stopping short of each of said end walls whereby slots are formed extending across the base at each end of said top wall, a cigarette receptacle on said top wall, means mounting said receptacle for sliding movement longitudinally of said wall, said receptacle having a discharge opening toward each end of the receptacle, said receptacle slidable on said base from end to end thereof to dispose first one discharge opening over the slot at one end of the top wall and then its other discharge opening over the slot at the other end of said top wall, a rocker element in said base, a support on each end portion of said element and said supports located to move inwardly and outwardly through said slots as said element is rocked, said supports adapted to receive cigarettes discharged through the respective discharge openings of said receptacle when the receptacle is at the respective ends of the base, and means whereby sliding movement of said receptacle results in rocking of said element.

7. In a cigarette box, an elongated hollow base including side and end walls and a top wall, said top wall stopping short of each of said end walls whereby slots are formed extending across the base at each end of said top wall, a cigarette receptacle on said top wall, means mounting said receptacle for sliding movement longitudinally of said wall, said receptacle having a discharge opening toward each end of the receptacle, said receptacle slidable on said base from end to end thereof to dispose first one discharge opening over the slot at one end of the top wall and then its other discharge opening over the slot at the other end of said top wall, a rocker element in said base, a support on each end portion of said element and said supports located to move inwardly and outwardly through said slots as said element is rocked, said supports adapted to receive cigarettes discharged through the respective discharge openings of said receptacle when the receptacle is at the respective ends of the base, spaced knobs on said rocker element and adapted both to extend upwardly through openings in said top wall inwardly of the ends thereof when said rocker element is balanced, and said knobs adapted to be engaged and depressed by the receptacle to shift first one and then the other of said supports through its slot as said receptacle is shifted first to one end and then to the other of said base.

8. In a cigarette box, an elongated hollow base including side and end walls and a top wall, said top wall stopping short of each of said end walls

whereby slots are formed extending across the base at each end of said top wall, a cigarette receptacle on said top wall, said base having guideways therein and said receptacle having flanges in said guideways whereby the receptacle is mounted for sliding movement longitudinally of said wall, said receptacle having a discharge opening toward each end of the receptacle, said receptacle slidable on said base from end to end thereof to dispose first one discharge opening over the slot at one end of the top wall and then its other discharge opening over the slot at the other end of said top wall, a rocker element in said base, a support on each end portion of said element and said supports located to move inwardly and outwardly through said slots as said element is rocked, said supports adapted to receive cigarette discharged through the respective discharge openings of said receptacle when the receptacle is at the respective ends of the base, and spaced knobs on said rocker element and adapted to be engaged and depressed by the receptacle to shift first one and then the other of said supports through its slot as said receptacle is slid first to one end and then to the other of said base.

9. In a cigarette box, an elongated base having a slot-like opening adjacent each end, a pair of supports associated one with each of said slots, a rocker element in said base, means whereby as said element is rocked said supports are moved in alternate order outwardly and inwardly through the respective slots, a receptacle slidable on the base from end to end thereof and adapted when moved to either end of the base to deposit a cigarette on the support adjacent that end, means whereby sliding movement of said receptacle results in rocking of said element, and means limiting rocking movement of said element to a very short arc whereby to maintain said supports relatively close to and substantially aligned with said slots in all positions of said element.
